UNITED STATES PATENT OFFICE

ELI BECKER AND ISAAC MILLER, OF CLEVELAND, OHIO

DESIGN FOR A BOTTLE

Application filed April 11, 1931. Serial No. 39,456. Term of patent 14 years.

To all whom it may concern:

Be it known that we, ELI BECKER and ISAAC MILLER, citizens of the United States, residing at Cleveland, in the county of Cuyahoga and State of Ohio, have invented a new, original, and ornamental Design for Bottles, of which the following is a specification, reference being had to the accompanying drawings, forming a part thereof.

In the drawings:

Fig. 1 is a side elevational view showing a bottle embodying our design.

Fig. 2 is a view similar to Fig. 1 with the bottle rotated 90° from the position shown in Fig. 1.

We claim:

The ornamental design for a bottle substantially as shown.

Signed by said ELI BECKER and ISAAC MILLER at Cleveland, in the county of Cuyahoga, and State of Ohio, this 8 day of April, 1931.

ELI BECKER.
ISAAC MILLER.
